APPARATUS FOR GRINDING

Frederich G. Krafft, Springfield, Ohio, assignor
to The Thompson Grinder Company, Springfield, Ohio, a corporation of Ohio

Application September 21, 1946, Serial No. 698,500

9 Claims. (Cl. 51—94)

1

This invention relates to methods and apparatus in connection with grinding machines. More particularly, this invention relates to a method of grinding workpieces and to a novel fixture for supporting the workpieces during the said grinding thereof.

The particular object of the present invention is the provision of an improved process and mechanism for the production of thread rolling dies. Dies of this nature comprise substantially flat plates which have threads formed thereon. In use, a pair of such dies are placed face to face and form threads on a screw or workpiece by rolling it therebetween under pressure. This is a fast and economical way of forming threads of commercial accuracy. While the thread dies are in some cases flat, it is preferable that they include an inclined portion over about one-half their length and have rounded end portions. The rounded end portions facilitate the entry and exit of a workpiece to and from the pair of dies while the inclined portion simulates a feed so that the threads are gradually rolled into the workpiece.

Heretofore, the production of thread dies of this nature was attended with difficulty because of the aforementioned rounded and inclined portions of the surface thereof. In order properly to grind a die of this nature it is essential that it be ground from end to end in a single pass of the grinding wheel. This necessitates adjustment of the position of the wheel and workpiece relative to each other. Formerly it was attempted to move the grinding wheel toward and away from the workpiece during the grinding operation but it was found that inferior workpieces resulted due to the great inertia of the grinding wheel and its supporting structure. Also, former grinding techniques involved the use of a wheel having a single thread formed thereon so that in the forming of a thread rolling die it was necessary to make several passes across the workpiece and to duplicate the movements of the die and wheel relative to each other on each pass.

With the present invention the foregoing difficulties are eliminated by grinding a thread rolling die at a single pass, and by moving the said die radially toward and away from the grinding

2 wheel in order to obtain the desired configuration.

Accordingly, the principal object of the present invention is to provide a method and apparatus for grinding workpieces such as thread rolling dies with a single pass of the grinding wheel.

A still further object is the provision of an improved workpiece holding fixture for grinding machines which moves the workpiece relative to the wheel in order to grind predetermined contours thereon.

These and other objects and advantages will become more apparent upon reference to the following description taken in connection with the attached drawings in which:

Figure 1 is a fragmentary view of a grinding machine showing the grinding wheel, the workpiece supporting fixture, and a dressing means for dressing the periphery of the wheel;

20 Figure 2 is a view similar to Figure 1 but partially broken away to show the mechanism for actuating the grinding wheel table and a portion of the mechanism for tilting the workpiece supporting fixture;

25 Figure 3 is a transverse section indicated by the line 3—3 in Figure 1 and showing other details in connection with the construction of the workpiece holding fixture;

Figure 4 is a plan view of a workpiece being 30 ground showing the manner of supporting the same on the fixture;

Figure 5 is a view taken substantially along the line 5—5 of Figure 3;

Figure 6 is a fragmentary view showing a portion 35 of the dressing mechanism for a grinding wheel;

Figures 7, 8 and 9 are views showing the fixture and workpiece at different stages of a grinding cycle.

40

General arrangement

According to this invention it is desired to grind thread forms or the like in a die plate from end to end and to form the said plate with a relieving fillet at each end and with a tapered or inclined portion extending from one end part way to the other. For accomplishing this result, the workpiece is supported on a fixture having suitable chuck means such as electric or magnetic chuck. The fixture is supported for movement toward and

away from the grinding wheel by eccentric shafts or cams at either end thereof. By individually rotating these shafts or cams, the fixture can be tilted in order to move the workpiece relative to the wheel thereby to form the desired configuration.

The fixture is mounted on a reciprocable table that is slidably carried on a machine bed and also carried on the bed are stationary cams which are engaged by roller arms on the eccentric shafts which support the fixtures. Thus, as the table reciprocates on the bed, the aforementioned roller arms engage the stationary cams on the bed and cause the fixture to tilt in timed relationship with the movements of the bed.

According to this invention, the grinding wheel is preferably dressed by a dressing roller so that the entire width of the die plate is ground at one time. While the workpiece can be ground by a single pass thereacross, it will be understood that it is also possible to grind the workpieces by means of a first rough grind and a second lighter and finish grind.

Structural arrangement

Referring to the drawings more in detail, Figures 1, 2 and 3 show a portion of a grinding machine having a bed 10 on which is reciprocably mounted a table 12. A suitable motor means such as the hydraulic cylinder 14 and piston 16 with the plunger 18 may be employed for reciprocating the said table on the bed.

Stationarily supported in adjustable relationship with the bed and table is a grinding wheel 20 rotatable by a shaft 22 which is connected with any suitable motor means such as an electric motor of the proper speed and power. Carried on the table 12 and beneath the wheel 20 is a workpiece holding fixture 24 constructed according to the present invention.

The fixture 24 consists of a base plate 26 which is directly mounted on the table 12 and which is aligned therewith by means of a key 28 secured to the bed plate and extending into a T-slot on the said table. The bed plate 26 may be secured to the bed in a suitable manner such as by hold-down clamps, screws or the like.

At each end of the bed plate 26, there are a pair of spaced journal boxes as indicated at 30 and 32 in Figure 3. The journal boxes at the other end of the bed plate are indicated by the numerals 30' and 32'. Referring to Figure 3, it will be noted that the journal box 30 includes an anti-friction bearing 34 while the journal box 32 includes an anti-friction bearing 36. The journal boxes at the opposite end of the bed plates are similarly equipped with anti-friction bearings.

Extending through the journal boxes 30 and 32 is a shaft 38 having an intermediate eccentric portion 40. Similarly, there is a shaft 42 which extends through the journal boxes 30' and 32' and which has an intermediate eccentric portion 44. The workpiece holding fixture 24 is directly supported on the eccentric portions of the aforementioned shafts by a pair of wear plates 46, 48 secured to the underneath side of the said fixture at either end thereof. For preventing the fixture 24 from shifting laterally there may be provided pads or guide plates as at 50 and 52 on the fixture which bear against the collars 54 and 56 respectively which are fitted over the shaft 38.

The fixture 24 is held against longitudinal movement by a pair of depending lugs 58 and 60 on the underneath side thereof which embrace therebetween a ball 62 which is fixedly secured

to the bed plate 26. By means of the aforementioned guides the fixture 24 may be tilted by rotation of the shafts 38 and 42 and occupy a predetermined position for each position of the said shafts.

Referring to Figure 3, it will be noted that the shaft 38 has connected therewith an extension shaft 64 which is journaled in the outboard anti-friction bearing 66 and which has connected with its extended end an arm 68 that carries a roller 70. The roller 70 is adapted for engagement with a cam 72, best seen in Figure 1, which is secured to a stationary bar 74 which is fixedly carried on the bed 10 as by the brackets 76. The connection of the cam 72 with the bar 74 is by the screw means indicated at 78 which pass through a foot connected with the cam and extend into the T-slot 80 in the said bar.

The shaft 38 is continuously urged in a clockwise direction as viewed in Figure 1 by a torsion spring 82 which has one end connected with the arm 68 and its other end anchored on the journal box 32. For insuring that the shaft 38 will stop in a predetermined position relative to the fixture 24 the right end thereof preferably carries a stop pin 84 that is carried in a collar 86 pinned to the said shaft. The stop pin 84 is adapted for engagement by a second stop pin or stationary abutment 88 which is carried in the journal box 30.

The shaft 42 at the opposite end of the fixture 24 is similarly fitted with an arm 90 that carries a roller 92 for engagement with a second cam 96 also adjustably carried on the bar 74. The shaft 42 likewise has a torsion spring which continuously urges the said shaft in a counterclockwise direction into a stopped position provided for by abutment means similar to the pins 84 and 88.

Referring to the cam 72 more particularly, this will be seen in Figure 1 to comprise a relatively long inclined portion 96, and an abrupt rise at 98. The cam 94 on the other hand is substantially flat except for an abrupt rise thereon indicated at 100.

In the grinding of a workpiece, the workpiece is placed on the fixture 24 as is shown at 102 in Figure 4. In order to insure that the threads cut on the workpiece will lay at the proper angle, there is provided a helix bar 104 which abuts the workpiece on one side and which is in turn abutted by the straight edged bracket 106. The fixture 24, as mentioned before is preferably an electric or magnetic chuck so that the workpiece when positioned as indicated in Figure 4 is firmly secured to the surface of the workpiece fixture.

After the workpiece is in position, a grinding cycle is carried out as indicated in Figures 7, 8 and 9. The grinding wheel is set in motion and the table 12 is moved toward the right. At this time, the roller 70 is riding on the high part of the cam 72 so that the shaft 38 is rotated into position to cause the eccentric portion 40 thereof to elevate the right end of the fixture 24. With the fixture so elevated the table moved rightwardly to bring the grinding wheel into engagement with the workpiece 102 at the corner marked 108. Further movement to the right of the table causes the roller 70 to roll down the incline 96 of the cam 72 so as continuously to rotate the shaft 38 to bring about the progressive lowering of the fixture 24. This causes the wheel to grind a fillet or curved relief portion at 108 on the workpiece.

As movement of the table to the right progresses the roller 70 rolls down the incline 96 of the cam 72 so as continuously to rotate the shaft 38 to bring about the progressive lowering of the fixture 24. This action is effective to cause

the wheel to cut the straight inclined portion indicated at 110 on the workpiece.

When the rightward movement of the table has progressed to the point where the shaft 38 is stopped in its rotation, the wheel is positioned at the beginning of the straight portion 112 of the workpiece. Thereafter, the movement of the table to the right causes no tilting of the fixture 24 until the roller 92 meets the rise 100 of the cam 94. When this occurs, the shaft 42 is rotated clockwise and the eccentric portion 44 thereof lifts the left end of the fixture 24 so that the grinding wheel cuts the fillet or relief portion indicated at 114 on the workpiece. It will be apparent that the fixture 24 is guided throughout the grinding cycle by the guiding pads shown at 50, 52 and the collars 54 and 56 and the ball guide 62 together with the brackets 58 and 60.

Following the grinding of the workpiece, if it is desired to true the wheel the table may be moved to bring the grinding wheel 20 directly over the dressing roller indicated at 116. Thereafter, the wheel may be dressed by running it together with the said roll under pressure and with no slipping therebetween. This type of dressing is known as crush dressing or crush forming of the wheel and is particularly well adapted for the work cycle illustrated in the present application.

In order to make the arrangement of this invention adaptable for workpieces of different sizes, the bar 74 may carry scale marks as indicated at 118 which register with the marks 120 and 122 carried by the supporting feet of the cams 72 and 94. It will be apparent that the present invention provides a method of, and apparatus for, grinding a workpiece including fillets and inclined surfaces as well as flat surfaces in a standard grinding machine without in any way altering the said machine except to provide a suitable support for the cam carrying bar 74. Thus, by practicing the methods of this invention and utilizing the apparatus thereof, the field of use of a standard grinding machine is greatly extended and workpieces which have heretofore only been formed with great difficulty, may be ground rapidly, accurately, and economically.

It will be understood that this invention is susceptible to modification in order to adopt it to different usages and conditions and, accordingly, it is desired to comprehend such modifications within this invention as may fall within the scope of the appended claims.

I claim:

1. In a grinding machine; a rotatable grinding wheel; a workpiece supporting fixture; eccentric means supporting said fixture at each end; an arm on each eccentric means; a cam for each arm; means for relatively reciprocating said wheel and fixture for grinding a workpiece carried on the latter; and means for simultaneously moving said arms and cams relatively for actuating said eccentric means for a predetermined sequence of tilting movements of said fixture.

2. A fixture for supporting a workpiece on a machine table comprising; a base rigidly securable to the table; a workpiece supporting member; guide means for limiting the movements of said member on said base to tilting movements or to movements of the member directly toward and away from said base; eccentric means engaging said member at spaced points; and means operable automatically as the machine table is reciprocated for actuating said eccentric means in rotation for tilting said member to contour a workpiece thereon.

3. In a machine tool; a bed; a table reciprocable on said bed; a fixture comprising a base rigidly secured to the table and a workpiece supporting member carried on the base; guide means preventing lateral or longitudinal movements of said member on said base while permitting tilting movements thereof; an eccentric shaft supporting said member at each end; an arm on each shaft; cam means on said bed to engage and actuate said arms; and means for reciprocating said table on said bed whereby said member goes through a predetermined tilting cycle for each stroke of said table.

4. In a machine tool having a relatively reciprocable cutting means and workpiece supporting table; a fixture comprising a base rigidly securable to said table; a workpiece supporting member on said base; guide means limiting the movement of said member relative to said base to tilting movements in a single plane; spaced eccentric means journaled in said base and directly supporting said member; an arm on each said eccentric means; cam means operable when said arms and cam means move relatively to actuate said eccentric means; and means for synchronously actuating said cutting means and table, and said cam means and arms in relative reciprocating movements.

5. In a fixture for supporting a workpiece to be machined; a base; a pair of spaced eccentric shafts journaled in said base; a workpiece holding member supported on said shafts; yielding means continuously urging said shafts in one direction; stop means to halt said shafts in the said one direction to predetermine a position of said member; an arm on each shaft; cam means to engage and actuate said arms; and means operable in synchronism with the traversing of said workpiece by a cutting tool for moving said cam means relative to said arms.

6. In a fixture for supporting a workpiece while it is being machined; a base; an eccentric shaft journaled in each end of said base; yielding means continuously urging said shafts into predetermined stopped positions; a workpiece holding member supported on said shafts; guides holding said member against transverse movement on said base; a ball guide extending from said base intermediate said shafts; bracket means on said member embracing said ball guide; and means for oscillating said shafts for tilting said member during the machining of a workpiece thereon.

7. In a grinding machine having a bed and table reciprocable thereon; a fixture on said table comprising a base rigid thereon; a work holding member guided on said base for tilting movements; an eccentric shaft at each end of said base supporting said member; an arm on each shaft; cam means for actuating said arms to rotate said shafts for tilting said member; and bracket means on said bed for supporting said cam means in alignment with said arms.

8. In a grinding machine having a bed and table reciprocable thereon; a fixture on said table comprising a base rigid thereon; a work holding member guided on said base for tilting movements; an eccentric shaft at each end of said base supporting said member; an arm on each shaft; separate cam means for actuating said arms independently to rotate said shafts for tilting said member; and bracket means on said bed for adjustably supporting said cam means in alignment with said arms.

9. In a grinding machine having a bed and table reciprocable thereon; a fixture on said table

comprising a base rigid thereon; a work holding member guided on said base for tilting movements; an eccentric shaft at each end of said base supporting said member; an arm on each shaft; cam means for actuating said arms to rotate said shafts for tilting said member; and graduated bracket means on said bed for separately supporting said cam means in alignment with said arms and for independent adjustability.
